CLIP-TYPE SHIELD

Rupert L. Evans, Hollywood, Fla., assignor to
Crossly Window Corp., Dade, Fla.
Filed Apr. 27, 1965, Ser. No. 451,156
6 Claims. (Cl. 49—501)

ABSTRACT OF THE DISCLOSURE

An integral, clip-type shield for use over the end of a stile which has a U-shaped slot for reciprocably receiving a monorail of a header, in which the shield includes a plate-like body having tine-carrying, displaceable tabs for grippingly engaging the stile on opposite sides of the U-shaped slot thereof and enclosing said slot for cushioning the monorail during relative movement between the stile and header.

This invention relates to a clip-type shield, and, more particularly, to a clip-type shield receivable as a liner for a U-shaped slot in the end of a sliding panel stile to guide the panel for sliding movement relative to a track depending from a header.

As is perhaps well known, sliding panels are quite often provided with a U-shaped slot in the ends of the stiles of the panel to receive a guide track of a header which moves relative to the slot walls on sliding movement of the panel. In the past, it has been found desirable to provide a nylon liner for the slot which is secured to the stile by means of screws passed through flanges on either side of the liner. This invention provides a clip-type guide shield for the end slots of such stiles which includes integral fastening means whereby auxiliary fasteners are not required to secure it to the stile.

It is, therefore, an object of this invention to provide a clip-type shield or guide of tough, resilient, synthetic elastic material to line the U-shaped slot of the stile of a panel to receive a guide track or monorail therein and for sliding movement relative thereto, said shield including integral gripping means to secure it in position.

It is another object of this invention to provide a shield of the type described hereinafter which is relatively simple in construction, is inexpensive to manufacture, and is otherwise well adapted for the purposes for which it is intended.

In accordance with these and other objects which will become apparent hereinafter, the instant invention will now be described with reference to the accompanying drawings in which:

FIG. 1 is an exploded partial perspective view of the header of a frame and the stile of a sliding panel and illustrating the instant shield in perspective relation to the header and stile;

FIG. 2 is a second perspective view of the guide; and

FIG. 3 is a side elevation view of the shield installed on the stile in FIG. 1.

Referring more particularly to the drawings, wherein like reference characters designate like or corresponding parts throughout the different views, and referring particularly to FIG. 1, the numeral 11 generally designates the clip-type shield which is tough, durable, elastic, synthetic material, such as nylon, which, by reason of its structure, as is set forth more fully hereinafter, is resilient and adapted to cling in place on a sliding panel in the position shown in FIG. 3.

Referring to FIG. 1, the numeral 12 generally designates a channel-form header of a closed frame, such as that commonly installed in building openings, to accommodate sliding movement of a panel protectively nested between the flanges 18 and 20 and guided in sliding move-

2

ment by a monorail 22 depending from the web 16. The numeral 14 generally designates the stile of the panel which is ordinarily of an extruded length of metallic material having a stile side 25 with a U-shaped slot 24, having a floor 26 and vertical side walls 28 and 30, to receive the monorail or guide track 22 therein. On either side of the floor of the slot screw holes 32 and 34 are provided to accommodate passage of headed screws for engagement with elements carried in the panel but which form no part of the instant invention and are, therefore, not shown. Above the holes two recesses 36 and 38 are ordinarily provided to receive screws to hold a shield in place, and the edges of which recesses, it will be seen, are utilized to co-operate with tines 70 and 72 of the instant clip-type shield 11 to securely connect it in the slot 24 of the stile.

Referring in detail to the clip-type shield 11, seen in FIGS. 1 and 2 in perspective, it comprises a relatively thin plate body 40 or flange to overlay the interior surface of the stile side 25 and a first and a second tine-carrying tab 50 and 52 held in spaced-apart and confronting relation with respect to the plate as flanges of the U-shaped slot liner. The side walls of the liner 54 and 56 are sufficiently thick to cushion the stile relative 25 to the web 22 and are sized so as to completely and snugly overlay the floor and side walls of the slot 24. The upper surface of the shield is flat to ride smoothly under a header web when installed and the walls of the mouth of the slot are thickened to normally constrict the mouth 30 to define wiper edges 58 and 60 of web-gripping cushion surfaces 66 and 68. The lips of the mouth 62 and 64 are beveled inwardly to the cushion surfaces of maximum constriction 66 and 68; it is noted that the said confronting cushion surfaces of the constricted mouth are generally vertical between the lips and at the entrance to the main width of the slot. As can be seen in FIG. 2, the tines 70 and 72 respectively confront recesses 46 and 48 in the plate portion of the body, the said tabs being congruent with respect to the recesses but with the tines 35 opposing a portion only of the recesses which is outwardly of the slot walls. As can be seen in FIGS. 1 and 2, each of the tines is arrow-shaped to define a barb edge for a purpose which will become apparent in the next paragraph.

45 In assembly, the guide shield is positioned in the symmetrical relation shown in FIG. 1 above the stile slot 24 with the U-shaped liner of the shield being pressed depthwise into the slot with the plate overriding the inner stile surface until the arrowed edges or slanted surfaces 50 of the tines ride onto the outer surface of the stile side. Continued downward pressure on the shield expands the distal edges of the tabs away from the plate body a slight distance about the hinge lines, i.e., the lines of connection with the U-shaped liner, which also draws the mouth to a slightly constricted portion, by reason of the fact that the distance between the opposing faces of the tabs and the plate is the same as that of the thickness of the stile and the constriction of the mouth takes advantage of the increase of the distance between the tabs and the plate resulting from the movement of the distal edge of the tabs with respect to the aforesaid hinge lines. As continued pressure is applied to press the shield downwardly into the slot, the tines snap into the recesses 36 and 38 of the stile as the barb edges clear to relax the tabs with respect to the hinge line, and, substantially simultaneously, the mouth relaxes to the open position as the pressure causing the outer edges of the tabs to expand and the edges of the tines is relieved and, therefore, the tine edges move into tight abutting engagement with the side walls of the recesses of the stile. Thus, the shield is securely fastened in the stile without requiring

additional fastening means with the liner or spacer portions protectively lining the slot and the cushion surfaces being adapted to snugly wipe and grip the web when the panel is assembled thereto, the said beveled edges guiding the distal end of the mono-rail into the slot 49. Further, by reason of the fact that in the preferred construction the tabs as seen in elevation are at least congruent to the recesses 46 and 48 of the plate portion of the body and the tines are in abutting engagement with the outer edge of the stile recesses, the tabs protectively overlay the recesses of the stile face to protect it from the elements. In the preferred embodiment, the inherent resiliency of the plastic material, which is preferably nylon, and which holds the tines into tight engagement in the stile recesses and, also, the U-shaped liner in expanded relation into abutting engagement with the sides of the slot, may be supplemented by slightly bending the distal edges of the tabs toward the plate body and by forming the liner walls with an angle of divergence slightly larger than the included angle of the slot, when the shield is molded. Further, the apron or skirt of the plate in which the holes 42 and 44 are provided is of such a length that the screw holes 32 and 34 of the stile are in alignment when the clip-type shield is in place. Thus, it is seen that by reason of the structure aforesaid, the shield is adapted to be quickly and securely snapped in position on a stile and without the use of tools whereby it can then be moved as a unit to a site for panel assembly without the requirement of additional fastening means to accompany the stile and shield.

While the instant invention has been shown and described herein in what is conceived to be the most practical and preferred embodiment, it is recognized that departures may be made therefrom within the scope of the invention, which is therefore not to be limited to the details disclosed herein, but is to be accorded the full scope of the claims so as to embrace any and all equivalent apparatus and articles.

What is claimed is:

1. A clip-type shield comprising, a plate-type body having a slot centrally of one edge extending into the body, a first and second clip tab, one of said tabs on each side of the slot and in spaced-apart relation in a plane parallel to the main plane of the body, spacer portions connecting the tabs and the body and defining slot walls, extending between the planes of the confronting surfaces of the plate and tabs, and each of said tabs having a tine on the surface confronting the plate for grippingly engaging therebetween the edges of a recess in a slotted stile when the clip-type shield is positioned in the slot of the stile with the spacer lining the slot of the stile. 40

2. An integral, clip-type guide shield of tough, resilient, synthetic, plastic material for snug seating in a U-shaped slot at the end of a stile to receive a guide rail therein depending from the web of a header comprising; a congruent liner sized for insertion in overlaying relation to the walls of the U-shaped slot, and resilient holding means to maintain the shield liner in the slot, said holding means comprising a flanged lip of plate form on one side of the liner to overlay a portion of one surface of the stile around the liner and a first and a second coplanar flanged tab on the other side of the liner, 45

5 each tab to overlay a portion of the stile in diametrical opposition of the center line of the opening of the liner, a tine on each tab confronting the lip, the distance between the confronting surfaces of the tabs and the lip being substantially equal to the thickness of the stile and the line of connection between the tabs and the liner being flexible so that the distal end of the tabs are adapted to be resiliently expanded to normally contract and trap the tines in recesses in the stile. 4

10 3. In combination, a stile having a U-shaped slot at one end and a recess on each side of the slot and an integral, clip-type guide shield of tough, resilient, synthetic, plastic material for snug seating in the U-shaped slot to receive a guide rail therein depending from the 15 web of a header, said shield comprising a liner sized to overlay the walls of the U-shaped slot and resilient holding means to maintain the shield liner in the slot, said holding means comprising a flanged lip of plate form on one side of the liner to overlay a portion of one surface of the stile around the liner and a first and a second coplanar flanged tab on the other side of the liner, each tab to overlay a portion of the stile in diametrical opposition of the center line of the opening of the liner, a tine on each tab confronting the lip, the distance between the 20 confronting surfaces of the tabs and the lip being substantially equal to the thickness of the stile and the line of connection between the tabs and the liner being flexible so that the distal end of the tabs are adapted to be resiliently expanded to normally contract and trap the 25 tines in recesses in the stile. 30

35 4. An integral, clip-type guide shield of tough, resilient, synthetic, plastic material for snug seating in a U-shaped slot at the end of a stile to receive a header therein depending from the web of a flange comprising, a congruent liner sized for insertion in overlying relation to the walls of the U-shaped slot, said shield comprising:

a plate-like body member having a slot opening into one side thereof, side walls flanking said last-mentioned slot and extending away from one side of said plate-like body member, displaceable tabs extending laterally from said side walls away from said last-mentioned slot and in spaced relation from said one side of said plate-like body member and confronting the same, said tabs including tines extending toward said one side of said plate-like body member whereby the stile is grippingly engaged thereby.

5. The structure as claimed in claim 4 in which said plate-like body member includes recesses therein in opposed relation to terminal end portions of said tines.

6. The structure as claimed in claim 4 in which said side walls include integral, web-gripping cushions extending into said last-mentioned slot and in confronting, spaced relation.
